UNITED STATES PATENT OFFICE.

TITUS RUSSELL, OF ALBION, MICHIGAN, ASSIGNOR TO HOLLAND FURNACE CO., OF HOLLAND, MICHIGAN.

CLEANING DEVICE FOR HOT-AIR-FURNACE PIPES.

Application filed April 5, 1924. Serial No. 704,524.

This invention relates to cleaning devices and has more particular reference to a means whereby the pipes of hot air furnaces may be readily relieved of their soot without the necessity of disassembling the same.

The primary object of the present invention is to provide a cleaning device of the above character that includes suction and brushing means operable by a suitable power plant that may be inserted through the furnace pipes for adequately sucking the dirt and soot from the interior thereof.

A still further object of the present invention is to provide cleaning means for hot air furnace pipes that include interchangeable parts whereby the exterior surface of the furnace pipes may be also cleaned and this in such a manner as to prevent the spattering of the dust throughout the cellar 20 or other rooms of the home or building.

An additional and important object is to provide means of the above character wherein a motor vehicle engine may be equipped with devices for the operation of the suction and brushing mechanism in the 25 operation of the vehicle engine.

An additional object is to provide means for permanent attachment to the power shaft of a vehicle engine and particularly one of the Ford automobile type whereby the suction pipe of the present invention and the 30 rotary cleaning brush may be detachably associated therewith.

With the foregoing and other objects in view, as the nature of the invention will be better understood, the same comprises the novel form, combination and arrangement of parts hereinafter more fully described, shown in the accompanying drawings and 35 claimed.

In the drawings wherein like reference characters indicate corresponding parts throughout the different views,

Figure 1 is a fragmentary plan view of the front end of an automobile of the Ford type equipped with a suction fan operable through the medium of a connection to the engine crank shaft, said connection being partly shown in cross section and said suction fan adapted to have associated therewith a suction pipe of a flexible nature and of a suitable length that may be inserted within the furnace pipes in the cleaning of soot, etc., from the interior thereof,

Figure 2 is a detailed sectional view

through the connection between said suction fan and the crank shaft of the vehicle engine, said suction fan being fragmentarily shown in cross section,

Figure 3 is a front elevational view of the suction fan per se, the front removable wall thereof being partly broken away,

Figure 4 is a side elevational view of a brush carrying mechanism that is equipped with means operable by the suction of the air passing therethrough in the rotation of the brush, said brush mechanism being detachably associated with the forward end of the before mentioned flexible pipe as shown and said flexible pipe being fragmentarily shown in longitudinal cross section for disclosing more clearly the construction thereof, the attachment to the fan casing being indicated at the left,

Figure 5 is a front end elevational view of said brush mechanism disposed within a pipe for setting forth more clearly the means for maintaining said brush mechanism centrally disposed within the pipe and against relative vibratory movement therein.

Figure 6 is a detail transverse cross sectional view of the flexible pipe taken substantially upon the line 6-6 of Figure 4, and

Figure 7 is a detail longitudinal sectional view of another form of suction operable brushing means that may be detachably associated with the end of the before mentioned suction pipe for use in the cleaning of the exterior surfaces of the stove pipes.

First having particular reference to Figures 1, 2 and 3 of the drawings, my invention includes among other elements, a desirable form of universal joint designated generally 5, preferably of the type that includes a relatively large circular collar 6 and a relatively smaller collar 7, the opening through which is of an angular nature. This form of universal joint is generally well known, and the collars 6 and 7 are formed with spaced radial fingers at their adjacent ends interposed between which is a leather disk 8 which is connected to the fingers of the collars through the medium of bolt and nut connections as shown.

The innermost collar 6 of this universal joint 5 is adapted for engagement over the usual inner rim of the fan belt pulley A upon the end of the crank shaft of an engine B, preferably of the type serving as a power

plant for an automobile machine designated generally C. Adapted for insertion through the usual crank handle bearing upon the front frame member of the automobile, is a rod shaft 9 the opposite ends of which are beveled and multi-sided, the innermost end adapted for engagement within the foremost collar 7 of said universal joint 5.

Rigidly attached to the opposite frame 10 bars a—a of the automobile machine and at the front end thereof are plates 10—10 the forward ends of which extend beyond the radiator of the machine as shown in Figure 1, said forward ends thereof being rounded.

15 Adapted for rigid attachment to the front end of the machine C through the medium of said plates 10—10 is a suction fan designated generally by the reference character 11. As clearly shown in Figure 3 this suction fan constitutes the provision of a front 20 open-sided circular casing 12 that is formed with a tangential discharge 13. The rear wall of said casing 12 is formed with a central opening 14 through which is extended 25 a bearing sleeve 15 formed centrally of a fan wheel 16 disposed within said casing 12. This sleeve 15 is journaled within a bearing collar 17 that is carried by an angle bar 18 welded or riveted to the rear wall of said 30 fan casing 12.

The opposite ends of this angle bar 18 are formed with upstanding fingers 19—19 that are in turn formed with sleeves 20—20 for arrangement upon the front rounded ends 35 of said plate 10—10 upon the vehicle chassis bars a—a. Said sleeves carry set screws 21—21 whereby the fan units may be rigidly secured in position upon the front end of the automobile.

40 The forward end of the rod shaft 9 above described is adapted for engagement within the fan wheel carrying sleeve 15 whereby when the motor B is operated, a rotation will be imparted to the fan wheel 16 for 45 drawing air through a central collared opening 22 formed centrally of the fan casing cover plate 23 that may be rigidly attached to the open side of the casing in a manner preferably as shown in Figure 3.

50 Adapted for rigid detachable engagement with the collar of said fan casing cover plate opening is one end of a flexible hose 23' of any desirable length, it being of course necessary that the length of this hose be sufficient to enable the same to be passed entirely through the different pipes of a hot air furnace. This hose 23' is preferably constructed of an impervious casing 24, Figure 4, within which are arranged longitudinally 55 extending spaced straps 25 to which are attached spaced metal bands or rings 26, for obviously preventing the collapsing of the tube casing.

60 Adapted for detachable rigid engagement upon the forward end of said hose 23' are

brush units designated generally 27 and 28 in Figures 4 and 7, respectively.

The brushing unit 27 is adapted for association with the hose 23' when it is desired to clean the interior of stove pipes. This 70 unit constitutes the provision of a relatively elongated sheet metal collar 29 for arrangement at its inner end over said end of the hose. At the front and rear ends of said collar 29 there is formed cross bars 30 centrally of each of which is formed a shaft bearing 31 through which is extended a suction fan shaft 32. Intermediate the bearing supports for said shaft the same carries two 75 or more longitudinally extending curved 80 blades 33 through the medium of which said shaft is rotated by the impinging of the air, dirt or soot thereagainst which is drawn into this unit through the medium of the suction fan 11 upon the vehicle. 85

The forward end of the fan shaft 32 extends a distance beyond the collar 29 and the same is formed with a transverse opening 34 within which may be secured wire bristles 35 through the medium of a set screw or 90 other locking means 36.

It will of course be obvious that when this unit 27 is inserted within a pipe through the medium of a hose 23' an actuation of the brush member per se as well as the 95 suction member will entirely relieve the interior of the pipe of all dust, dirt, soot, etc.

For maintaining the unit 27 centrally 100 within the pipe D, Figure 5 and against relative vibratory movement therein, the collar 29 of the unit is equipped with a plurality of longitudinally extending spaced outwardly bulged leaf spring members 37 that are secured at their forward ends to the outside of the collar 29 and that are 105 slidable at their inner free ends through guide brackets 38 carried by said collar. It will be manifest that the nature of these springs 37 is such as to permit the proper disposition of the brush unit 27 within stove 110 pipes of various diameters.

The unit 28 as disclosed in Figure 7 is to be used in the cleaning of the exterior surfaces of the furnace pipes and in this instance said unit constitutes the provision of a collar 39 that is adapted to be arranged upon the end of the hose 23' in lieu of the before described unit 27. At the front and rear ends of this collar 39 are also cross arms 40—40 that are formed centrally with bearing members 41 within which are arranged the opposite end of a fan shaft 42 that carries fan blades 43 similar in all respects to the fan blade 33 of the unit 27. 115

The forward end of this collar 39 is provided with a bent finger shaped pipe section 44 that may consist of a multiplicity of pivotally jointed sections. The under side of this pipe section 44 is formed with a longitudinal opening 45 that increases in 120 125 130

depth at the inner end of the section toward the forward end thereof for purposes herein-after to be more fully described.

Arranged within this pipe section 44 are 5 a plurality of shaft hangers 46 and extending through the pipe section is a sectional shaft 47 that is journaled within said hangers and the sections of which are joined together through the medium of universal 10 joints 48. Each of these shaft sections 47 carries a cylindrical-shaped brush element 49 and it will be obvious that in actual use this curved finger pipe section 44 is adapted to be engaged over the external 15 surface of a pipe and the operation of the brushes 49 through the medium of the rotation of the fan within the collar 39 under the action of the suction fan 11 of the present mechanism the dirt will be brushed 20 from the pipe and effectively drawn inwardly through the collar and then into the hose 23' and subsequently out of the fan casing tangential outlet 13 to be caught in a bag or other suitable container.

25 It will thus be seen that I have provided a highly novel and efficient means for clean-

ing the interiors and exteriors of stove pipes and even though I have herein shown and described a particular manner in which the movable elements namely, the suction fan 30 and brush operating fan are operated, it is nevertheless to be understood that departures may be had from the showing without affecting the spirit and scope of the appended 35 claim.

Having thus described my invention, what I claim as new and desire to secure by Letters Patent, is:—

In a pipe cleaning apparatus a flexible 40 suction hose, a collar carried by the hose, bowed springs anchored at one end upon the exterior of the collar and adapted to engage the interior of a pipe, rotary blades 45 journaled for rotation in the collar to rotate about the axis of the collar and curved longitudinally of the collar to be rotated by the current of air exhausted thereinto, cleaning brush element exterior of the said collar connected to the blades and adapted to be driven by the action of the blades.

In testimony whereof I affix my signature.

TITUS RUSSELL.
